[57] CLAIM

The ornamental design for a rechargeable battery pack for kitchen appliance, as shown and described.

DESCRIPTION

FIG. 1 is a view in perspective from the top, one side and one end of a rechargeable battery pack for kitchen appliance showing our new design;

FIG. 2 is a front end elevational view thereof;

FIG. 3 is a rear end elevational view thereof;

FIG. 4 is a left side elevational view thereof, the right side being a mirror image;

FIG. 5 is a top plan view thereof; and

FIG. 6 is a bottom plan view thereof.

FIG. 1

FIG. 2

FIG. 3

FIG. 4

FIG. 5

FIG. 6
